UNITED STATES PATENT OFFICE.

WINTHROP K. HOWE, OF ROCHESTER, NEW YORK, ASSIGNOR TO GENERAL RAILWAY SIGNAL COMPANY, OF GATES, NEW YORK, A CORPORATION OF NEW YORK.

CIRCUIT-CONTROLLER.

1,276,767.

Specification of Letters Patent. Patented Aug. 27, 1918.

Application filed July 3, 1916. Serial No. 107,356.

To all whom it may concern:

Be it known that I, WINTHROP K. Howe, a citizen of the United States, and a resident of the city of Rochester, in the county of Monroe and State of New York, have invented a new and useful Circuit-Controller, of which the following is a specification.

This invention relates to circuit controllers, and more particularly to circuit controllers for governing the operating circuits of automatic trips or similar signal appliances which have a biased position and an operated position.

One of the objects of this invention is to devise a novel, simple and reliable circuit controller, especially adapted for use with automatic trips, which will open and close the governing circuits of the motor and of the retaining mechanism associated with said trip at the proper times and in proper sequence.

A further object of the invention is to devise a circuit controller having the characteristics above mentioned, and which may also be used to properly control the signal associated with the trip.

Other objects and advantages will appear as the description of the invention progresses, and the novel features of the invention will be particularly pointed out in the appended claims.

In describing the invention in detail, reference is had to the accompanying drawing, wherein I have illustrated a preferred physical embodiment of my invention, and wherein like characters of reference designate corresponding parts throughout the several views, and in which:

Figure 1 is a side elevation of a circuit controller embodying the invention shown applied to a trip, parts of the circuit controller and the mechanism associated with said trip being broken away;

Fig. 2 is a vertical section taken substantially on the line 2—2 in Fig. 1 and looking in the direction of the arrow *a*;

Fig. 3 is a vertical section taken substantially on the line 3—3 in Fig. 1 and looking in the direction of the arrow *b*; and

Fig. 4 is a diagrammatic view of an arrangement of wiring which may be used with the circuit controller shown in Figs. 1, 2 and 3.

In the accompanying drawing one form of a circuit controller embodying this in-

vention has been illustrated as applied to the well known automatic trip; and the numeral 1 designates the shaft to which the trip arm is attached. According to the arrangement and construction ordinarily employed and which is contemplated in the illustrated application of the circuit controller embodying the invention, the shaft 1 is biased by a weight, or other suitable means to rotate in one direction so as to bring the trip arm attached thereto into position to engage the valve arm carried on a train; and suitable power mechanism, herein assumed to be an electric motor and its associated gearing, is employed to turn the shaft 1 against the opposition of its bias into the position where the trip arm will not engage the valve arm of a passing train, suitable mechanism being provided for retaining the shaft 1 in this latter position. For simplicity the electric motor, its operating gearing, and the mechanism for retaining the shaft 1 in its clear position, have not been illustrated, it being understood that this mechanism may be of any well known or suitable construction.

The circuit controller comprises two end brackets, 2, which are fastened to supports 3 in any suitable way as by tap bolts 4, it being understood that the supports 3 form a part of, or are secured to the frame or case of the mechanism for operating the automatic trip. Secured to the end brackets 2 are parallel contact supporting bars 5 and 6 of any suitable insulating material, and secured to these bars 5 and 6 are a number of contact fingers of suitable construction arranged in opposed pairs. In the form of the invention illustrated, the circuit controller comprises three parts or units designated A, B and C, and each of these units includes two pairs of contact springs, the contact springs associated with the unit A being designated 7—7 and 8—8, and the similar contact springs associated with the unit B being designated 9—9 and 10—10. The construction of the unit C is the same as the construction of the unit A, and is illustrated as showing the manner in which the unit A may be duplicated if desired to perform similar functions.

Referring to Figs. 1 and 2, the unit A includes a circuit controlling lever or member 12, journaled on a shaft 11 extending between and secured to the end brackets 2.

This circuit controlling member 12 comprises a stem 13 to which is attached in any suitable manner the block 14 of insulating material; and to the block 14 in turn is fastened a metallic contact strip 15. The circuit controlling member 12 also comprises a rib 16 in which a hole 17 is formed near each end and on opposite sides of the shaft 11. The lower end of the rib is shaped to 10 form a downwardly projecting lug 18, and integral with the hub of the circuit controlling member 12 is a mating lug 19, the lugs 18 and 19 constituting in effect a downwardly opening jaw. Extending between 15 the end brackets 2 is a rod 20, which is held in place by short pins 21 fixed therein; and a tension coil spring 22 has one end hooked around the rod 20 and its other end hooked in the upper hole 17 in the rib 16 of the circuit controlling member 12.

The units A, B and C of the circuit controller are operated by the shaft 1 by means of a rockarm 23, which is split and clamped on the shaft 1 by a tap bolt 24. The rockarm 25 is bifurcated, and the separate bifurcations 25 of this rockarm 23 terminate in bosses or in enlargements 26. Extending through the bosses 26 is an operating rod 27 which is held in place by pins 28, said 30 operating rod 27 being disposed between the lugs 18 and 19 of the circuit controlling member 12.

Referring to Figs. 1 and 3, the unit B of the circuit controller is similar in construction in many respects to that of the unit A, and comprises a circuit controlling member or lever 12¹ journaled on the shaft 11 but in the unit B, the stem 29 of the circuit controlling member 12¹ has a notch or groove 30 40 therein in which fits the stem portion of a contact carrier block 31, said stem portion being narrower than the notch 30 and being mounted on a pin 32 fixed in the stem 29 so as to permit a limited amount of rocking 45 movement of said contact carrier block 31 relative to said stem 29. The contact carrier block 31 is substantially T-shape, the head portion thereof being arranged to contact with the stem 29 of the circuit controlling member 12¹; and secured to said contact carrier block is a piece 33 of suitable insulated material to which is secured a contact strip 34. The contact member 12¹ has a rib 35 in which are holes 36; and the 55 lower end of the rib 35 forms a downwardly projecting lug 38, which is disposed opposite to a mating lug 39 integral with the hub of the member 12¹. A tension spring 37 is hooked over the rod 20 at one end and at 60 the other end is hooked into the upper hole 36 of the rib 35 of said circuit controlling member. The operating rod 27 is disposed between the lugs 38 and 39 of the circuit controlling member 12¹ in the same way as 65 said operating rod is disposed between the

lugs 18 and 19 of the circuit controlling member 12.

Referring to Fig. 4 there is shown diagrammatically an arrangement of controlling circuits suitable for use with a circuit controller embodying the invention. The motor for operating the trip shaft 1 is designated M; and the retaining mechanism, commonly called a hold clear device, which serves to hold the trip shaft 1 in its clear 70 position is designated HC. The automatic trip may be controlled in any suitable way; but in the diagrammatic illustration in Fig. 4, said automatic trip is controlled by a track relay T having an armature 40. The signal 80 associated with the automatic trip stop may be of any suitable construction; but is shown in Fig. 4 as comprising a red lamp R and a green lamp G.

The operation of the circuit controller 85 illustrated in Figs. 1, 2 and 3 may be readily understood in connection with the following description of the operation of the automatic trip from one end of its positions to another position. In Fig. 4 the parts of the circuit controller and the parts of the automatic trip shown are illustrated in the position corresponding to the position in which the trip arm is held down clear of the valve arm of a passing train. When the trip arm is in 95 its clear position the hold clear device HC is energized by a circuit which may be traced as follows:

Commencing at the battery 41, conductor 42, armature 40 of the track relay T in its 100 upper position, conductors 43 and 44, the hold clear device HC, conductor 45, contact spring 10, contact strip 34, contact spring 10, and conductors 46 and 47, back to the battery 41.

The green lamp G, indicating proceed is lighted by a circuit which may be traced as follows:

Commencing at the battery 48, conductors 49 and 50, lamp G, conductor 51, contact spring 8, contact strip 15, contact spring 8 and conductors 52 and 53, back to the battery 48.

When a train enters the block which is guarded by the automatic trip, the track relay T is deenergized, as will be clearly understood by those skilled in the art, and the armature 40 of said track relay T drops and interrupts the circuit hereinbefore traced which energizes the hold clear device HC, 115 thereby permitting the shaft 1 to turn under the influence of its bias to the position in which the trip 1 secured thereto will engage the valve arm on a train attempting to pass said automatic trip. During this movement 120 of the shaft 1 to its biased position, the circuit controlling members 12 and 12¹ are pulled by the springs 22 and 37, respectively, into the position opposite to that shown in Figs. 2 and 3. The contact strip 15 of the 130

circuit controlling member 12 now breaks contact with the contact spring 8 thereby interrupting the circuit for the green lamp G, and makes contact with the contact spring 7, thereby closing a circuit for the red lamp R, which may be traced as follows:

5 Commencing at the battery 48, conductors 49 and 57, lamp R, conductor 58, contact spring 7, contact strip 15, contact spring 7, 10 and conductors 59 and 53, back to the battery 48.

When the shaft 1 moves to its biased position, the contact strip 34 is moved from contact with the contact springs 10 and into contact with the contact springs 9 so that, after a train has left the block guarded by the automatic trip and the track relay T is energized, the motor M is energized by a circuit which may be traced as follows:

20 Commencing at the battery 41, conductor 42, armature 40 of the track relay T in its upper position, conductors 43 and 54, motor M, conductor 55, contact spring 9, contact strip 34, contact spring 9, and conductors 56 and 47, back to the battery 41.

When the motor M is energized it drives the shaft 1 in the direction indicated by the arrow X, Figs. 2 and 3, to move the trip arm to its clear position. During the first part of 30 this movement of the shaft 1, the circuit controlling members 12 and 12¹ remain stationary, since they are held in the position they then have by the springs 22 and 37, and since the operating rod 27, which is in 35 contact with the lugs 19 and 39, respectively, at the beginning of this movement of said shaft 1 to the clear position, may move a limited distance before it strikes the lugs 18 and 38, respectively. After this first part 40 of the movement of the shaft 1 to its clear position, the circuit controlling members 12 and 12¹ are moved with the shaft, and during the final movement of said shaft 1 to its clear position, circuit controlling member 12 45 is moved to the position shown in Fig. 2, thereby extinguishing the red lamp R and lighting the green lamp G. At the same time the circuit controlling member 12¹ is moved to substantially the position shown in 50 Fig. 3, in which the circuit for energizing the motor M hereinbefore traced, is broken, and in which the circuit for energizing the hold clear device HC is completed. After the operating circuit of the motor M is 55 broken, there will ordinarily be a slight continued movement of the shaft 1, due to the momentum of the parts; but, on the other hand, before the hold clear device HC becomes effective, it may happen that the shaft 60 1 will settle back under the influence of its bias, nearly if not entirely as much as said shaft continued to move after the operating circuit for the motor M was interrupted.

It is obvious that unless some special means 65 is provided, the circuit controlling member

12¹ will move, as the shaft 1 settles back, to a position to reestablish the motor operating circuit which will result in the shaft 1 moving back to its full clear position; whereupon, before the hold clear device HC is 70 effective, the shaft 1 will settle back again; and this back and forth movement of the shaft 1 may continue indefinitely and produce the objectionable "pumping" of the trip shaft 1 and the trip arm secured thereto. According to this invention, however, when the shaft 1 settles back and as a consequence the circuit controlling member 12¹ 75 also moves to the left, as viewed in Fig. 3, the friction between the contact spring 10 80 and the contact strip 34 retards or holds back the contact carrier block 31; and since this contact carrier block 31 is loosely connected to the circuit controlling member 12¹, considerable movement of said member 12¹ 85 to the left, as viewed in Fig. 3, may take place without causing said block 31 to move correspondingly to the left. In this way the shaft 1, after it has been operated by a motor M to its full clear position, may settle 90 back without operating the contact carrier including the block 31, so as to interrupt the circuit for energizing the hold clear device HC. This loose or lost motion connection 95 between the circuit controlling member 12¹ and the contact carrier block 31 forms an important feature of this invention.

It should also be noted that the circuit controlling member 12, which in the particular application of the invention illustrated 100 controls the signal lamps R and G, changes from the position shown in Fig. 2 to the opposite position after only a slight movement of the shaft 1; or in other words, the green lamp G is extinguished and the red 105 lamp R is lighted after a slight movement of the shaft 1 toward its biased position. This slight movement may be selected such that at or before the trip arm on the shaft 1 is in position to automatically stop a passing 110 train, the red lamp R, indicating stop or danger will be lighted. On the other hand, when the shaft 1 is in its biased position and is being operated by the motor M to its clear or operated position, the circuit controlling member 12 lags behind the movement of said shaft 1, so that the shaft 1 115 must assume its full clear position before the red lamp R is extinguished. In a similar way, when the shaft 1 is in its operated or 120 clear position, the circuit controlling member 12¹ commences to move to the left as shown in Fig. 3 as soon as the shaft 1 starts to move toward its biased position; and when the shaft 1 is in its biased position, the circuit controlling member 12¹ lags behind the movement of said shaft 1 toward its operated position so that the operating circuit for the motor M is maintained until the shaft 1 reaches its full clear position. 125 130

Although I have particularly described the construction of one physical embodiment of my invention, and explained the operation and principle thereof; nevertheless, I desire to have it understood that the form selected is merely illustrative, and does not exhaust the possible physical embodiments of the idea of means underlying my invention.

What I claim as new and desire to secure by Letters Patent of the United States, is:

10. 1. In a circuit controller for railway signaling appliances, in combination: a movable circuit controlling member pivotally supported between its end and having spaced lugs at one end; an insulated contact piece carried by the same member at its other end; fixed contact fingers arranged to coöperate with the contact piece in the different positions of said member; a spring connected to said member and tending to move in one direction; an oscillatable shaft disposed parallel to the axis of movement of said member; a rocker arm fixed to the shaft; and a rod carried by the outer end of 15 the rocker arm and adapted to fit loosely between the lugs of said member, whereby the movement of said member from one circuit controlling position to the other is caused at one extreme of the range of movement of the shaft.
20. 2. In a circuit controller, in combination: an oscillatable shaft; a movable circuit controlling member comprising a pivotally supported arm and a contact member loosely connected thereto; a spring tending to move said circuit controlling member in one direction; and means constituting a lost motion connection between said shaft and said member.
25. 3. In an electrically operable device, in combination: a shaft biased to turn in one direction, electrically operable means for turning said shaft in the opposite direction; retaining mechanism for holding said shaft in its operated position; controlling circuits for said electrically operable means and for said retaining mechanism; and circuit controlling means governed by said shaft for selectively controlling said circuits, said 30 means comprising two parts loosely connected, and one of said parts being operatively connected to said shaft.
35. 4. In a circuit controller, in combination: an oscillatable shaft; a circuit controlling member comprising two parts loosely connected,
40. 5. In an electrically operable device, in combination; an oscillatable shaft biased to turn in one direction; electrically operable means for turning said shaft in the opposite direction; retaining mechanism for holding said shaft in its operated position; controlling circuits for said electrically operable means and for said retaining mechanism; and circuit controlling means governed by said shaft for selectively controlling said circuits, said 45 means comprising two parts loosely connected, and one of said parts being operatively connected to said shaft.
50. 6. In an electrically operable device, in combination; an oscillatable shaft biased to turn in one direction; electrically operable means for turning said shaft in the opposite direction; retaining mechanism for holding said shaft in its operated position; controlling circuits for said electrically operable means and for said retaining mechanism; and circuit controlling means governed by said shaft for selectively controlling said circuits, said 55 means comprising two parts loosely connected, and one of said parts being operatively connected to said shaft.
55. 7. In an electrically operable device, in combination; an oscillatable shaft biased to turn in one direction; electrically operable means for turning said shaft in the opposite direction; retaining mechanism for holding said shaft in its operated position; controlling circuits for said electrically operable means and for said retaining mechanism; and circuit controlling means governed by said shaft for selectively controlling said circuits, said means comprising two parts loosely connected, and one of said parts being operatively connected to said shaft.
60. 8. In an electrically operable device, in combination; an oscillatable shaft biased to turn in one direction; electrically operable means for turning said shaft in the opposite direction; retaining mechanism for holding said shaft in its operated position; controlling circuits for said electrically operable means and for said retaining mechanism; and circuit controlling means governed by said shaft for selectively controlling said circuits, said means comprising two parts loosely connected, and one of said parts being operatively connected to said shaft.
65. 9. In an electrically operable device, in combination; an oscillatable shaft biased to turn in one direction; electrically operable means for turning said shaft in the opposite direction; retaining mechanism for holding said shaft in its operated position; controlling circuits for said electrically operable means and for said retaining mechanism; and circuit controlling means governed by said shaft for selectively controlling said circuits, said means comprising two parts loosely connected, and one of said parts being operatively connected to said shaft.
70. 10. In an electrically operable device, in combination; an oscillatable shaft biased to turn in one direction; electrically operable means for turning said shaft in the opposite direction; retaining mechanism for holding said shaft in its operated position; controlling circuits for said electrically operable means and for said retaining mechanism; and circuit controlling means governed by said shaft for selectively controlling said circuits, said means comprising two parts loosely connected, and one of said parts being operatively connected to said shaft.
75. 11. In an electrically operable device, in combination; an oscillatable shaft biased to turn in one direction; electrically operable means for turning said shaft in the opposite direction; retaining mechanism for holding said shaft in its operated position; controlling circuits for said electrically operable means and for said retaining mechanism; and circuit controlling means governed by said shaft for selectively controlling said circuits, said means comprising two parts loosely connected, and one of said parts being operatively connected to said shaft.
80. 12. In an electrically operable device, in combination; an oscillatable shaft biased to turn in one direction; electrically operable means for turning said shaft in the opposite direction; retaining mechanism for holding said shaft in its operated position; controlling circuits for said electrically operable means and for said retaining mechanism; and circuit controlling means governed by said shaft for selectively controlling said circuits, said means comprising two parts loosely connected, and one of said parts being operatively connected to said shaft.
85. 13. In an electrically operable device, in combination; an oscillatable shaft biased to turn in one direction; electrically operable means for turning said shaft in the opposite direction; retaining mechanism for holding said shaft in its operated position; controlling circuits for said electrically operable means and for said retaining mechanism; and circuit controlling means governed by said shaft for selectively controlling said circuits, said means comprising two parts loosely connected, and one of said parts being operatively connected to said shaft.
90. 14. In an electrically operable device, in combination; an oscillatable shaft biased to turn in one direction; electrically operable means for turning said shaft in the opposite direction; retaining mechanism for holding said shaft in its operated position; controlling circuits for said electrically operable means and for said retaining mechanism; and circuit controlling means governed by said shaft for selectively controlling said circuits, said means comprising two parts loosely connected, and one of said parts being operatively connected to said shaft.
95. 15. In an electrically operable device, in combination; an oscillatable shaft biased to turn in one direction; electrically operable means for turning said shaft in the opposite direction; retaining mechanism for holding said shaft in its operated position; controlling circuits for said electrically operable means and for said retaining mechanism; and circuit controlling means governed by said shaft for selectively controlling said circuits, said means comprising two parts loosely connected, and one of said parts being operatively connected to said shaft.
100. 16. In an electrically operable device, in combination; an oscillatable shaft biased to turn in one direction; electrically operable means for turning said shaft in the opposite direction; retaining mechanism for holding said shaft in its operated position; controlling circuits for said electrically operable means and for said retaining mechanism; and circuit controlling means governed by said shaft for selectively controlling said circuits, said means comprising two parts loosely connected, and one of said parts being operatively connected to said shaft.
105. 17. In an electrically operable device, in combination; an oscillatable shaft biased to turn in one direction; electrically operable means for turning said shaft in the opposite direction; retaining mechanism for holding said shaft in its operated position; controlling circuits for said electrically operable means and for said retaining mechanism; and circuit controlling means governed by said shaft for selectively controlling said circuits, said means comprising two parts loosely connected, and one of said parts being operatively connected to said shaft.

WINTHROP K. HOWE.
